Primary Examiner—Jeffrey Asch

(74) Attorney, Agent, or Firm—Banner & Witcoff, Ltd.

(57) **CLAIM**

The ornamental design for a portion of an audiovisual communication device, as shown and described.

DESCRIPTION

FIG. 1 is a front perspective view of a portion of an audiovisual communication device showing our new design;

FIG. 2 is a front view thereof;

FIG. 3 is rear view thereof;

FIG. 4 is a right view thereof;

FIG. 5 is a left view thereof; and,

FIG. 6 is a top view thereof.

The unshown bottom forms no part of the claimed design. The broken line showing of various regions and the unshaded regions therein are for illustrative purposes only and form no part of the claimed design.
